TOBACCO STEMMING MACHINE

William A. Brandt, Salem, Va., assignor to Comas
Cigarette Machine Company, Salem, Va., a cor-
poration of Virginia

Application July 19, 1932, Serial No. 623,449

7 Claims. (Cl. 131—57)

This invention relates to an improvement in tobacco stemming machines, and more particularly to cleaning rolls for such machines.

In the forms of cleaning rolls which have heretofore been proposed and used, it has been found that the stems and lamina of the tobacco leaves wrap around the rolls and work into the teeth and wires on the card clothing covering the rolls, so that the rolls fail to clean the stripping brushes effectively and the leaves have a tendency to follow back through the machine.

The object of my present invention is to provide cleaning rolls which will successfully clean the lamina and stems from the stripping brushes and successively engage each stripping brush gradually from end to end without striking it with a solid blow.

The rolls which have been found successful and practical for the accomplishment of this object have the teeth or wires arranged in a spiral extending from one end to the other with a substantial blank portion on the surface of the roll. The spiral may have a slight or a steep pitch, but one has been found very successful which has only a slight pitch and extends about the roll less than a complete convolution throughout its length, there being two rows of teeth or wires arranged in spiral formation on diametrically opposite sides of the preferred form of roll, although the number of rows of teeth is not material, as other successful forms have had different numbers of rows.

The teeth may be supported in various manners so as to be arranged in spiral shapes, but in my preferred form, they are mounted in a strip of material designed to be held in a spiral groove in the periphery of the roll which groove has undercut side edges to receive the edges of the strip and prevent it from being displaced from the groove. This provides a simple and effective manner of supporting the teeth in spiral form at the periphery of the roll.

In the accompanying drawings:

Fig. 1 is a sectional view through the stripping portion of a tobacco stemming machine, showing the cleaning rolls applied thereto;

Fig. 2 is a perspective view of one form of cleaning roll;

Fig. 3 is an end elevation thereof;

Fig. 4 is a detail longitudinal sectional view through an end portion of the cleaning roll;

Fig. 5 is a transverse sectional view there-through; and

Fig. 6 is a perspective view of a slightly different form of roll.

The invention is shown applied to a tobacco stemming machine of the type set forth in the application of Thomas E. Pasley, Serial No. 547,979, filed June 30, 1931, now Patent No. 1,930,406, granted October 10, 1933, a portion of which is represented in Fig. 1, wherein the frame of the machine is designated generally by the numeral 1 and carries superimposed endless chains 2, upon which are mounted stripping brushes 3 having teeth arranged to be brought together in cooperative relation to engage opposite sides of tobacco leaves which are fed between the endless chains by means of superimposed endless conveyors 4.

Arranged adjacent each of the endless chains 2 carrying the stripping brushes 3 are cleaning rolls 5 designated generally by the numeral 5 journaled in suitable bearings on the frame and adapted to be driven from the source of power which drives the chains 2 and conveyors 4, as set forth in the Pasley application, above referred to.

The peripheries of the cleaning rolls 5 carry teeth which are arranged in position to engage the teeth of the stripping brushes 3 to remove from the brushes portions of the stems or lamina which may stick thereto.

My present invention embodies improved forms of cleaning rolls which I have found to be very effective in cleaning the bits of tobacco leaves from the stripping brushes. Each cleaning brush is provided with a body portion 6, from the opposite ends of which project trunnions 7 received in journals on the frame for rotatably supporting the cleaning roll.

The body portion 6, is provided with grooves 8 formed in the periphery thereof, and extending generally in spiral shape lengthwise of the roll. Each of these grooves is undercut at its opposite edges to provide shoulders 9, wherein a strip of card cloth 10 or other suitable material of a width approximately corresponding with the width of the groove 8 extends lengthwise therein, so as to be disposed in spiral form in the periphery of the roll, as shown in Fig. 2. Each of the strips 10 carries car teeth 11, arranged in rows lengthwise thereof, although the teeth may be staggered or arranged as found desirable. Set screws 12, are threaded into the body portion 6, in the grooves 8, at the ends thereof, so as to hold the strips 10 against lengthwise displacement, but either or both of these screws may be removed whenever it is desired to replace the card clothing strips.

In the form shown in Figs. 1 to 5, there are two rows of card clothing teeth arranged on diametrically opposite sides of the roll and each row is shown as of the width of four teeth. Each row

extends about the roll less than a complete convolution throughout the length of the roll, so as to provide a very gradual spiral with a considerable space between succeeding spirals. The spiral shape of rows serve to cause the teeth to engage the stripping brushes gradually and successively to prevent the teeth from striking the brush simultaneously throughout its length. The space between the rows of teeth prevents portions of the leaves from clogging in the teeth and becoming wound onto the surface of the roll. It will be noted that the teeth are bent slightly at the portions which join the portions of the strip of card clothing, which bent portions allows the teeth to be self-cleaning.

In the modified form shown in Fig. 6 of the drawings, a strip of card clothing or other similar material 13 is wound spirally about the body portion 6, and which strip of material has its opposite ends fixed to the body portion by screws 14, extending into the body portion.

This strip 13 carries on the periphery of the roll, teeth 15 attached at such spaced apart portions thereof that when the strip 13 is wound in the form of a helical spiral, the teeth provide one or more rows extending in a generally spiral direction around the roll and lengthwise thereof, but the rows of teeth do not extend lengthwise of the card clothing strip.

In this form, the teeth are also arranged in spiral shape with sufficient space between the succeeding rows or convolutions that the lamination and bits of leaves or stems are effectively cleaned from the teeth of the stripping brushes but without clogging the cleaning rolls.

I have found through the use of these cleaning rolls that they effectively accomplish this desired purpose.

This application is a continuation in part of my application, Serial No. 569,811, filed October 19, 1931.

I claim:

1. A cleaning roll for a tobacco stemming machine comprising a body portion, a strip of material wound spirally thereon, and one or more rows of teeth extending transversely of each convolution of the spiral strip with blank spaces on opposite sides of the rows of teeth and in such position that the transverse rows of succeeding convolutions are approximately in longitudinal alignment forming one or more spiral rows extending about the surface of the roll.

2. In a tobacco stemming machine, the combination with leaf stripping means having card clothing teeth arranged for stripping the lamina from the stems, of a cleaning roll for said stripping means having one or more rows of card clothing teeth arranged on the periphery thereof, approximately in spiral shape, with each row extending through less than a complete convolution throughout the length of the roll.

3. In a tobacco stemming machine, the combination with stripping means having card clothing teeth arranged for stripping the lamina from the stems of the leaves, of a cleaning roll for the stripping means having rows of card clothing teeth on the periphery thereof, and arranged approximately on diametrically opposite sides of the roll with said rows extending generally longitudinally of the roll and extending spirally through less than a complete convolution throughout the length of the roll.

4. In a tobacco stemming machine wherein leaf stripping means having card clothing teeth is arranged for stripping the lamina from the stems, the combination of a cleaning roll having one or more rows of card clothing teeth arranged on the periphery thereof approximately in spiral shape with each row extending through less than a complete convolution throughout the length of the roll.

5. In a tobacco stemming machine wherein leaf stripping means having card clothing teeth is arranged for stripping the lamina from the stems, the combination with said stripping teeth, of a cleaning-roll having a longitudinal groove in the periphery thereof arranged approximately in a spiral shape, and a strip of material secured in said groove and carrying card clothing teeth in position to clean the lamina from the card clothing teeth of the stripping means.

6. In a tobacco stemming machine wherein leaf stripping means having card clothing teeth is arranged for stripping the lamina from the stems, the combination with said stripping teeth, of a cleaning roll having one or more longitudinal grooves in the periphery thereof, a strip of material extending in each groove and carrying a row of card clothing teeth in position to clean the lamina from the card clothing teeth of the stripping means, and means for holding the strip of material in said groove.

7. In a tobacco stemming machine wherein leaf stripping means having card clothing teeth is arranged for stripping the lamina from the stems, the combination with said stripping teeth of a cleaning roll having a plurality of longitudinal grooves formed in the periphery thereof and approximately in spiral shape, each of said grooves having undercut opposite edges, a strip of material extending longitudinally in each groove and having its opposite edges underlying the undercut edges thereof, preventing radial displacement of the strip of material, and means removably secured to the roll for normally preventing longitudinal removal of the strip from the groove, the strip of material carrying a row of teeth on the outer side thereof arranged in position for cleaning the lamina from the card clothing teeth of the stripping means.

WILLIAM A. BRANDT.
